LIFT FOR GIN BREASTS

Filed Feb. 16, 1923

2 Sheets-Sheet 2

UNITED STATES PATENT OFFICE.

CHARLES R. P. POOL, OF DALLAS, TEXAS.

LIFT FOR GIN BREASTS.

Application filed February 16, 1923. Serial No. 619,533.

To all whom it may concern:

Be it known that I, CHARLES R. P. POOL, citizen of the United States of America, residing at Dallas, in the county of Dallas and State of Texas, have invented certain new and useful Improvements in Lifts for Gin Breasts, of which the following is a specification.

This invention relates to new and useful improvements in lifts for gin breasts.

The invention has to do with certain improvements and additions to my invention covered by Letters Patent No. 1,380,677, issued June 7th, 1921.

15 A particular object of the invention is to provide means for latching the lifting lever, whereby the breast may be held in its lifted position and the lever released from the hand of the operator. Such an arrangement 20 prevents falling of the breast and gives a positive lock, so that the breast cannot be accidentally displaced, when lifted.

An advantage of the improvement is that no dependence is placed upon the position of 25 the lifting arm or the lug engaged by the same, as in my former patent and thus the manufacture may be simplified and a better arrangement had.

A construction designed to carry out the 30 invention together with other novel features will be hereinafter described.

The invention will be more readily understood from a reading of the following specification and by reference to the accompanying 35 drawings, in which an example of the invention is shown and wherein:

Fig. 1 is an end elevation of a portion of a gin stand showing the breast closed or lowered and an attachment embodying my invention applied thereto.

Fig. 2 is a transverse sectional view showing the gin breast raised.

Fig. 3 is a detail of the rock shaft and component parts,

45 Fig. 4 is a cross-sectional detail on the line 4-4 of Fig. 3.

Fig. 5 is a detail of the wear plate which is attached to the bottom of the breast, and

Fig. 6 is a detail of the arm and stop lug.

50 In the drawings the numeral 10 designates one of the end frames of a gin stand. The breast 11 is hinged to the stand at 12 and is constructed in the usual way and provided with a lower rib bar 13, the rest bar 14 and the usual sill 15. These parts are found in

the ordinary gin construction and form no part of my invention.

In carrying out the invention a longitudinal rock shaft 16 is provided and has one end supported in a bearing box 17 depending from the end frame 10, while its opposite end is supported in a bearing member or hanger 18 attached to the sill 15 at the central portion of the gin stand. The outer end of the rock shaft is preferably square in cross section and receives an arm 19 which is fastened thereon and projects upwardly on the outside of the frame 10 as is shown in Figs. 1 and 3.

The upper end of the arm is pivoted to 70 the rear end of a link 20 which extends forward and is pivoted to the lower end of an operating lever 21. The lever 21 is pivoted on a bracket 22 which latter is fastened to the end frame 10. The lever 21 is bent rearwardly and carries a handle 23 at its upper end. By grasping the handle and pulling the lever forward the link 20 is pushed rearwardly and the arm 19 thus swung rearwardly, whereby the rock shaft 16 is rocked. 80 The lever is pivoted on the bracket concentrically to a toothed segment 30 and carries a dog 31 pivoted above the segment so as to engage the teeth when the lever is pulled forwardly. A grip 33 is pivoted to the lever at the handle and is connected to the upper end of a rod 32 which has its lower end pivoted in an eye on top of the dog. By squeezing the grip toward handle 23 the rod is raised whereby the dog is lifted to free it 90 from the teeth of the segment. By this arrangement the lever may be latched in its forward position.

The inner end of the shaft 16 projects beyond the bearing member 18 and carries an arm 24, which it will be noted normally projects downwardly from the shaft 16. A pitman or lifting rod 25 has its rear end pivoted to the lower end of the arm 24 and extends thru a slot 26 in the bar 14. The bar 13 has on its rear side a wear socket 27 which is provided with a flange 28. By means of the flange 28 the socket is suitably fastened to said bar. The rod 25 has its forward end 25' reduced and engaging in the socket 27.

When the lever 21 is pulled forward the link 25 is swung rearwardly thereby swinging the arm 19 rearwardly whereby the shaft 16 is rocked and thus the arm 24 is swung upwardly whereby the rod 25 is pushed for-

wardly. When the rod 25 is moved forwardly the breast 11 will be lifted or swung outwardly as is shown in Fig. 2. It will be seen that the arm 24 is swung upwardly until its pivotal connection with the rod 25 is above a straight line running from the shaft 16 to the socket 27 and so long as the parts remain in this position the breast cannot be lowered or fall. When the breast 10 is thus elevated the dog 31 will be in engagement with the teeth of the segment 30 and the lever 21 will be pulled forwardly.

By grasping the handle 23 and pulling the lever forwardly the breast is elevated, 15 the dog riding over the teeth segment 30 and catching therein when the lever is brought to rest and the breast fully opened. By grasping the grip 33 and the handle 23 and squeezing the former against the latter, the 20 dog is raised from the segment and the lever swung rearwardly, whereby the breast is lowered. The latching means is positive and does not depend upon the joint between the arm 24 and the rod 25 to maintain the 25 breast in its lifted position. The lever has sufficient length above its pivot to provide ample leverage to enable the breast to be easily handled.

To limit the upward movement of the arm 30 24 a lug 29 is cast on each side of the same as is shown in Fig. 6. This lug engages a stop 29' on the member 18 and thus limits said upward movement. By casting the lug 29 on each side of the arm, the latter is 35 reversible so that the attachment may be applied to either end of the gin.

Various changes in the size and shape of the parts as well as modifications within the scope of the appended claims, may be made.

40 4. What I claim, is:

1. In a gin breast lifting attachment, a 45 rock shaft, means for supporting said rock shaft on a gin frame, a lever, means for fastening said lever in a forward position, a rocking connection between the shaft and the lever, means for mounting the lever on the gin stand, a lifting rod adapted to engage the breast of a gin, and means carried on the rock shaft for displacing the rod to lift 50 the breast when the shaft is rocked.

2. In a gin breast lifting attachment, a 55 rock shaft, means for supporting said rock shaft on a gin frame, a lever, a rocking connection between the shaft and the lever,

means for mounting the lever on the gin stand, a lifting rod adapted to engage the breast of a gin, means carried on the rock shaft for displacing the rod to lift the breast when the shaft is rocked by swinging the lever, said lifting means being arranged to automatically lock when the breast is raised to prevent lowering of the breast until the parts are swung out of locking position, and means carried by the lever for latching the same in position when the breast is lifted. 65

3. In a gin breast lifting attachment the combination with a gin stand and the breast thereof, of a rock shaft disposed longitudinally of the stand, an operating lever pivoted at one end of the stand, a rocking 70 connection between the lever and the shaft, a lifting rod engaging the breast, means carried by the rock shaft and connected with the rod for displacing the same to lift the breast, and means carried by the lever for 75 locking the same in position when the breast is lifted.

4. In a gin breast lifting device, the combination with a gin stand, of a rock shaft mounted on said stand, an operating lever pivoted on said stand, a locking segment mounted concentrically to the pivot of the lever, a dog mounted on the lever to engage the segment and fasten the lever in adjusted positions, means on the lever for lifting the 80 dog from engagement with the segment, an arm connected with the rock shaft, a link connecting the lever and the arm, a swinging element fastened on the rock shaft, and a lifting member pivoted to the swinging 85 element and engaging the breast for lifting the same.

5. In a gin breast lifting device, a rock shaft, means for supporting the shaft on a 90 gin frame, an arm fastened to one end of the shaft, a bracket for engagement with the end frame of a gin stand, a toothed segment on the bracket, a lever pivoted on the bracket, a dog pivoted on the lever and engaging the segment, a grip pivoted on the lever and connected with the dog for lifting the same, means connected with and operated by the shaft for lifting a gin breast when the lever is swung to rock the shaft, and a connection 95 between the lever and the arm. 100

In testimony whereof I affix my signature.

CHARLES R. P. POOL.
